[57] CLAIM

The ornamental design for a weatherproof electrical receptacle cover, as shown and described.

DESCRIPTION

FIG. 1 is a top, front perspective view of the weatherproof electrical receptacle cover showing my new design;

FIG. 2 is a top plan view thereof;

FIG. 3 is a side elevational view thereof, the opposite side being a mirror image;

FIG. 4 is a front elevational view thereof;

FIG. 5 is a rear elevational view thereof;

FIG. 6 is a bottom plan view thereof;

FIG. 7 is a perspective view thereof with one of the lids in the open position, it being understood that the interior elements disclosed by the second lid in the open position would be identical to those shown;

FIG. 8 is a front elevational view thereof with one of the lids in the open position.

The broken lines are shown in FIGS. 6, 7 and 8 for illustrative purposes only.
